LAWN SPRINKLER

Douglas W. Anderson, deceased, late of Palatine, Ill., by
Elizabeth A. Anderson, administratrix, Palatine, Ill.,
assignor to Burgess Vibrocrafter, Inc., Grayslake, Ill.

Filed Jan. 3, 1972, Ser. No. 215,236

Term of patent 14 years

Int. Cl. D23—01

U.S. Cl. D23—8

FIG. 1 is a perspective view taken from the front, top and right side of a lawn sprinkler showing my new design;

FIG. 2 is a rear elevational view thereof;

FIG. 3 is a left side elevational view thereof;

FIG. 4 is a perspective view taken from the rear, top and left side thereof;

FIG. 5 is a top plan view thereof; and

FIG. 6 is a right side elevational view thereof, showing the control elements in another position.

What is claimed is:

The ornamental design for a lawn sprinkler, substantially as shown.
